BLANK HANDLING APPARATUS FOR HEADERS

John H. Friedman, Tiffin, Ohio, assignor to The National Machinery Company, Tiffin, Ohio, a corporation of Ohio

Application March 12, 1951, Serial No. 215,142

2 Claims. (Cl. 10—12)

This invention relates to machines for successively performing a series of operations upon metal stock to produce blanks for screws, pipe plugs, and similar articles.

A machine for performing a plurality of operations upon blanks cut off from wire or rod stock is illustrated in the patent to Frost, 2,020,658, and such machines may include thread-rolling apparatus as shown in the patent to Frost, 2,020,659, and pointing mechanism as shown in my patent No. 2,020,660.

These machines are arranged to shear blanks from rod or wire stock and to upset and otherwise form the blanks in successive cooperative sets of tools and dies. Transfer means are arranged to transport the blanks to successive dies, such as the transfer mechanism illustrated in the patent to Clouse, No. 2,026,823.

In the machines illustrated in the aforesaid Frost patent, 2,020,658, and in my patent No. 2,020,660, the last station provided by the cooperating tools on the header slide and bed frame is a trimming station in which the blanks are pushed by a knockout from the final station on the die breast through a trimming die carried by the terminal tool on the header slide. The trimmed blanks are urged along a passageway formed in the header slide from which blanks are transferred either to a pointing mechanism mounted on the side of the bed frame, or to a collecting station. As explained in my Patent No. 2,275,103, it frequently happens that it is desired to form articles on such machines wherein the operation performed at the last tool and die set is not a mere trimming operation, but rather is an upsetting, gathering, or punching operation, with which the terminal tool must be solid and so may not have a blank receiving passageway formed therein.

In order to dispose of blanks in such machines, it has been proposed to provide an idle station in the die breast laterally spaced from the final die, there being a tool or other projection laterally spaced from the last forming tool on the header slide that ejects blanks from the transfer into the idle station and thereon through an outlet passageway in the bed frame. As explained in detail in my said Patent No. 2,278,103, this construction has the disadvantage that it requires an increase in width of the header slide in order to accommodate the blank ejecting tool on the slide which weakens the machine unless a very expensive and heavy bed frame construction is employed to compensate for the required increase in width of the slide. These difficulties are overcome in my aforesaid Patent No. 2,278,103, wherein an auxiliary transfer means is mounted on a transfer carriage for receiving and picking the blank from the last die when the knockout in the last die operates, and lifting the blank to a blank-receiving channel or guideway mounted on an upper portion of the machine. Mechanism driven by the machine and associated with the guideway is also provided to advance the blanks therethrough. Although this apparatus effectively solves the problem of holding header slide width to a minimum (where the last step is not a trimming operation but is a heading or other operation re-

quiring a solid tool), I have found that these same advantages may be obtained without need for a mechanically operated lift mechanism for the final transfer or ejector fingers by a novel arrangement of parts which are of unusually simple and economical construction, and which are exceptionally rugged in service.

Briefly, I have found that these advantages may be obtained by a simple and novel mechanism wherein a terminal or ejector set of transfer fingers is mounted on the transfer carriage, spaced a fixed distance from the adjacent regular transfer fingers by a distance equaling the spacing between the dies. Also, there is disposed in the die breast a knockout that is aligned with the row of dies and spaced from the last die by a distance equal to the nominal spacing between the dies. Finally the knockout device has its axis aligned with a blank-receiving tube having an inlet mouth facing the final or auxiliary knockout and formed in the side portion of the bed frame, the blank receiving tube is laterally spaced from but in the plane or row of the tools carried by the header slide. The timing of the cam or other means provided for operating the final knockout in the die breast, that is, the knockout opposite the blank-receiving tube, is different from the timing of the knockouts for the working dies, in that instead of ejecting the blank with the transfer carriage disposed toward the shearing station and with the header slide retracted, the auxiliary knockout is operated when the transfer carriage is away from the shearing station at which time the header slide is advanced and the auxiliary set of fingers is disposed in front of the blank-receiving tube. With the construction of the instant invention the operation at the last die may be a heading operation without requiring that the header slide be widened for employment of a tool to force blanks into an idle station and without requiring provision of an independently and vertically movable auxiliary transfer device and means to advance the blanks in the guide as disclosed in my said Patent No. 2,278,103.

The manner in which the foregoing and other advantages may be attained will be apparent from the following detailed description of a preferred form of the apparatus.

In the drawings:

Fig. 1 is a vertical section looking toward the bed frame dies of a cold header embodying the invention with the transfer in extreme right hand position.

Fig. 2 is a view like Fig. 1 with the transfer carriage in its extreme left hand position.

Fig. 3 is a horizontal section through the tool and die assembly of the apparatus;

Fig. 4 is a partial vertical section at the shearing station;

Fig. 5 is a detail of the ejector transfer fingers; and,

Fig. 6 is a somewhat diagrammatic illustrating the knockout timing.

The apparatus as shown is arranged to produce a blank having a head of circular section and a smaller square shank, such as a pipe plug blank. Cold headers and their accessories are well known to those skilled in the art and in the interests of clarity only so much of a double blow cold header as is necessary to understand the invention will be illustrated and described in detail.

The header includes a bed frame 10 having a transverse die breast 11 and a movable header slide 12 mounted in ways of guides 13 carried by spaced side portions of the frame. The die breast includes a plurality of dies D₁, D₂, and D₃, and the header slide includes cooperating tools T₁, T₂, and T₃ carrying punches P₁, P₂, and P₃. The header slide may be reciprocated by the usual crank-shaft as is well-known in the art, a suitable arrangement being disclosed in the patent to Clouse, 2,139,926. In the form shown, the device operates on wire or rod stock

S fed from a coil and advanced against a stock gauge G by intermittently-driven feed rolls as exemplified by the said patent to Clouse, 2,139,936, it being understood that details of the feeding mechanism are not critical to the invention.

The shear includes a vertically-reciprocating knife 14 mounted in a groove 15 in the die breast supported by a carrier 16, details of a suitable shear and operating mechanism being disclosed in the aforesaid patent to Clouse. The stock is fed through a feed opening 17 into the aperture of a shearing die 18 in the shear blade 14. As the blade rises, the blank O₁ is sheared from the stock and carried upwardly in alignment with the shear knockout K₁, which is urged in its retracted position by a spring 19. The timing and operation of the shear knockout K₁ and of the knockouts K₂, K₃, and K₄ for the respective die sets may be arranged as disclosed in the aforesaid patents to Clouse, 2,139,936 and 2,026,823, the details of this construction forming no part of the invention. However, the final or ejector knockout K₅ is out of phase with the others, in that it is actuated when the transfer fingers are to the right as seen in Figs. 1 and 2 instead of to the left. For example, if the knockouts K₁ to K₅ are, as seen in Fig. 6, actuated by cams C₁ to C₅ respectively (or by corresponding cam-actuated levers) actuator C₅ will be in the knockout position when the actuators C₁ to C₄ are in their retracted position.

A transfer mechanism T is arranged to reciprocate three pairs of transfer fingers 21 and 22 between the shear station and first die, and between successive dies. Said transfer mechanism is preferably made according to Clouse Patent 2,026,823. In accordance with the instant invention, a terminal set of ejector transfer fingers 23 is mounted on the carriage 31 to reciprocate with the transfer fingers 21 and 22. To receive the finished blanks from the ejector fingers 23, a tube or guideway is provided in the side portion of the bed frame and in alignment with the right hand position of the ejector fingers 23. A knockout K₅ is mounted in the die breast in alignment with the mouth of the tube 26. Means are provided to prevent finished blanks from falling out of the tube, including a ball 27 pressed by a spring 28 mounted in a housing 29 secured to the tube 26 near the mouth thereof.

The transfer assembly T includes a reciprocable carriage 31 which moves parallel to the line of a row of dies and is slidably supported in fixed guide member 32. Sets of cooperating arms 33 and 34 are pivoted to the carriage as at 35 and support respectively the three sets of transfer fingers 22 and 21. The fingers are closed to receive a blank and opened to clear the header tools by suitable mechanism (not shown) but described in the aforesaid patent to Clouse 2,026,823. In order to reciprocate the carriage, link means 37 and 38, operated by a crank 39 mounted on an oscillating shaft 41 are provided, a suitable time for this mechanism being disclosed in the aforesaid patent to Clouse, 2,026,823.

The terminal or ejector set of transfer fingers 23 is mounted on a plate 43 attached to the carriage 31 of the transfer assembly. The fingers are urged against a centering block 44, there being a guide pin 46 loosely mounted in an aperture 47 in block 44 and opposed compression springs 48 for urging the fingers inwardly so that they may grip the blank. Pin 49 guides the upper ends of the fingers and suitable fasteners 50 mount the assembly on the transfer carriage 31.

In operation, rod or wire stock S is fed through the feed opening 17 into a shearing aperture 18 in the shear blade 14 against a stock gauge G. In the first operation a blank O₁ is sheared from the stock, and as the shear rises it comes to rest in front of the first knockout pin K₁ which is advanced into the shear aperture by suitable cams or levers, and which may be urged to its retracted position by a spring such as 19. Upon retraction of the header slide 12, knockout K₁ pushes the sheared blank be-

tween the first pair of transfer fingers 21 and 22 which have been positioned to the left as shown in Fig. 2 of the drawings. The transfer operating mechanism is timed with respect to the header slide movement so that when 5 the header slide has receded from the die breast a sheared blank O₁ is presented to the first die D₁. Thereafter the header advances toward the die breast and the punch P₁, carried by the first tool T₁ is urged in its extended position by a spring as at 51, forces the blank O₁ into 10 the first die D₁, whereupon the sheared blank is beveled at one end to form the blank O₂. Knockouts for dies D₂ and D₃ are also operated in the usual timed relationship with respect to the transfer and header slide motions so that the blank is successively presented to the second 15 tool and die set T₂ and D₂ to form the extended blank O₃, and to the final tool and die set T₃ and D₃ to form the finished blank O₄. With the slide retracted and with transfer carriage to the left in the drawings, knockout K₄ forces the finished blank from die D₃ into the final 20 ejector or transfer fingers 23. Before advance of the slide is completed the transfer fingers are moved to the right as shown in Fig. 1 of the drawings, presenting new blanks to each die and carrying the completed blank D₄ to a position between knockout K₅ and tube 26. As 25 has been explained, the cam or other mechanism that operates knockout K₅ is out-of-phase with respect to the cam or mechanism which moves the shear and die knockouts in that knockout K₅ is advanced when the transfer carriage 31 is in its right-hand position. Then, with 30 the slide in a forward position the blank O₄ is forced by knockout K₅ from fingers 23 into tube 26. Tube 26 preferably leads upwardly and outwardly, and may conduct the blanks to a thread-rolling station or to a collecting station.

Having completed a detailed description of a preferred embodiment of my invention, it will be understood that various modification and changes therein may be made without departing from the essence of the invention as defined in the appended claims.

40 What is claimed is:

1. A header having a bed frame, an axially reciprocating slide, a die-breast on said bed frame, a die in said die-breast, a cooperating tool on said slide, means for supplying blanks to said die to be worked upon by said tool; a blank-receiving aperture in said bed frame to one side of said slide substantially horizontally aligned with said die, said aperture having an inlet mouth facing said die-breast and spaced axially therefrom to provide clearance for transfer means, said aperture leading exteriorly of said frame for conducting said blanks to a succeeding external station, transfer mechanism including blank transporting means mounted for reciprocation from a first position in front of said die to a second position in front of said blank-receiving aperture, a knockout slide in said die for ejecting a blank from said die into said blank transporting means with the latter in said first position, a blank ejector in said die-breast aligned with the mouth of said blank-receiving aperture for ejecting a blank from said blank transporting means into said aperture with the blank transporting means in said second position, and means to advance said knockout with said blank transporting means in said first position and to actuate said ejector with said blank transporting means in said second position, said means to advance said knockout and actuate said ejector being arranged so that the movement of the knockout and ejection is substantially 180° out of phase.

2. A header having a bed frame, an axially reciprocating slide, a die-breast on said bed frame, said die-breast and bed frame being formed to provide a notch on one side of said slide having axially opposed walls, a die in said die-breast, a cooperating tool on said slide, means for supplying blanks to said die to be worked upon by said tool; a blank receiving aperture in said bed frame substantially horizontally aligned with said die having an

inlet mouth formed in the wall of said notch that faces said die-breast, said aperture leading exteriorly of said frame for conducting said blanks to a succeeding external station, transfer mechanism including blank transporting means mounted for reciprocation from a first position in front of said die to a second position in front of said blank-receiving aperture, a knockout slideable in said die for ejecting a blank from said die into said blank transporting means with the latter in said first position, a blank ejector in the other wall of said notch and aligned with the mouth of said blank-receiving aperture for ejecting a blank from said blank transporting means into said aperture with the blank transporting means in said second position, and means to advance said knockout with said

blank transporting means in said first position and to actuate said ejector with said blank transporting means in said second position, said means to advance said knockout and actuate said ejector being arranged so that the movement of the knockout and ejection is substantially 180° out of phase.
